(57) **CLAIM**

The ornamental design for a liposuction cannula, as shown and described.

DESCRIPTION

FIG. 1 is a side perspective view of a liposuction cannula showing my new design;

FIG. 2 is a right side elevation view thereof. Left side elevation being the same view;

FIG. 3 is a top plan view thereof. Bottom view being the same view;

FIG. 4 is front elevation view thereof, and;

FIG. 5 is a rear elevation view.

The cannula is shown with a symbolic break in its length. The appearance of any portion of the article between the break lines forms no part of the claimed design.
